US0D1009955S

(12) **United States Design Patent** (10) Patent No.: **US D1,009,955 S**
(45) Date of Patent: ** Jan. 2, 2024

(54) **CASTING MACHINE**

(71) Applicant: **Bühler AG**, Uzwil (CH)

(72) Inventors: **Elias Schläpfer**, Dozwil (CH); **Raphael Walker**, Winterthur (CH); **Beat Eberle**, Wallisellen (CH)

(73) Assignee: **Bühler AG**, Uzwil (CH)

(**) Term: **15 Years**

(21) Appl. No.: **29/881,616**

(22) Filed: **Jan. 4, 2023**

Related U.S. Application Data

(62) Division of application No. 35/514,102, filed on Apr. 5, 2022 (U.S. filing date under 35 U.S.C. 384), and having an international filing date of Apr. 5, 2022, now Pat. No. Des. 992,609.

(30) **Foreign Application Priority Data**

Jan. 18, 2022 (EM) 008834501

(51) **LOC (14) Cl.** **15-09**

(52) **U.S. Cl.** ..... **USPC** **D15/135**
